UNITED STATES PATENT OFFICE.

GEORGE W. McMUNN, OF PITTSBURGH, PENNSYLVANIA.

DISTRIBUTION OF CARS IN YARDS.

1,242,220.

Specification of Letters Patent.

Patented Oct. 9, 1917.

Application filed November 8, 1916, Serial No. 130,202. Renewed August 23, 1917. Serial No. 187,888.

To all whom it may concern:

Be it known that I, GEORGE W. McMUNN, residing at Pittsburgh, in the county of Allegheny and State of Pennsylvania, a citizen of the United States, have invented or discovered certain new and useful Improvement in the Distribution of Cars in Yards, of which improvement the following is a specification.

10 In order to facilitate the distribution of cars composing a train in accordance with their ultimate destination, distributing yards are provided with an elevated section of track. A train of cars is pushed up this 15 elevated section and as one or more cars pass beyond the apex of the elevation, the coupling connecting the car or cars to the remainder of the train is released allowing the car or cars to roll down the opposite 20 side of the incline and onto a branch line, the end of the track on the delivery side of the elevated section being adapted to be connected by suitably arranged switches with any one of a plurality of branches. As soon 25 as the car or cars first cut loose have passed on to the proper branch track, the next one or two or more cars are uncoupled from the train and pushed over the apex of the elevated section from which they will pass onto 30 the proper branch, the proper switch or switches having been shifted. As the cars roll down the inclined rear side of the elevated section, they acquire considerable momentum and hence a brakeman usually rides 35 down with each car or section of cars to apply the brake at the proper time, and a yardman must attend so as to see that the couplings are in proper condition to insure a car being coupled to other cars on the 40 branches. By reason of carelessness, accidents frequently occur in the distribution or "drilling" of cars.

The invention described herein has for its object the provision of means whereby the movement of a car or cars along a branch track connected to the inclined section, as hereinafter described, can be controlled by an operator, stationed at a suitable point, preferably along the elevated section, and 45 who usually controls the switches for the distribution of the cars on the several branches. The invention is hereinafter more fully described and claimed.

In the accompanying drawings forming a 50 part of this specification, Figure 1 is a diagrammatic view, illustrating an elevated

track section and the branches radiating therefrom and connecting thereto by suitable switches, and also showing the connections leading from the station adjacent to the elevated track section for controlling the movement of the cars along the branch; Fig. 2 is a side elevation showing a car moving along one of the branches and provided with suitable connections extending 60 from the brake mechanism whereby the latter may be applied to the wheels of the car by a rail or plate arranged parallel with the rails of the branch track; Fig. 3 is a plan view of a car, the body of the car being removed and illustrating a portion of the brake mechanism and the connection whereby the brake mechanism may be caused to operate by the shifting of a plate or rail parallel with the track; Fig. 4 is a 65 view on a larger scale illustrating the manner of moving the plate or rail to operative position.

In the practice of the invention, plates or rails 1 are arranged preferably intermediate the rails 2 of the branch tracks and extending from a point adjacent to the foot of the elevated track section A for any desirable distance along the branch tracks. These plates or rails 1 are formed in sections for convenience of erection and operation, but are arranged so closely adjacent to one another as to be practically continuous for the full length of the branch tracks or such portion of such track section as is desirable to be provided with such rails or plates. As the plates or rails of the several branch tracks are to be shifted, as hereinafter described, to control the movement of the car or cars, suitable means are provided whereby such plates or rails may be raised to operative position by connections extending from a tower B, preferably arranged adjacent to the elevated track section. A convenient construction for shifting the rails or plates consists of a series of shafts 3 mounted in suitable bearings and transverse of the branch track and provided with arms 4 adapted to bear on the under side of plates or rails 1 and when shifted to raise the latter to the desired height. These shafts 3 are also provided with arms 5 connected by rods or pipes 6 to suitable operative levers in the tower B. Each car is provided with suitable means 100 adapted to frictionally engage the plates 1 when the latter are raised to operative posi- 105

tion and by reason of such frictional engagement to exert a pull through suitable connections, on the brake mechanism and cause the latter to apply the brakes to the 5 wheels of the car. A convenient construction to this end consists of a shaft 7 mounted in suitable bearings on one of the trucks, said shaft having small wheels 12 secured thereon, the shaft and wheels being so arranged that the latter will engage the plates 1 when raised and cause the shaft to rotate. To this shaft is secured one end of 10 a chain 8 passing around a grooved pulley 9, carried by an arm 10 connected to a lever 11 of the brake mechanism. The opposite end of this chain passes back substantially parallel with the main part of the chain a suitable distance where its end is attached to a suitable portion of the car. 15 As the shaft 7 is rotated, the main chain will be wound up thereon, shifting the lever 11 of the brake mechanism and applying the brakes.

In case it is desired to utilize the air 20 brake mechanism, a pipe 13 is connected to one of the pipes of the air brake under the car, and said pipe 13 is provided with an escape valve 14, having its operating arm connected to the brake lever or any other suitable part capable of being shifted by the 25 rotation of the shaft 12.

In using my improved apparatus, the operator in the tower watches a car as it 30 passes down the incline and along the branch track and as soon as it reaches the desired portion of such branch, or approaches another car standing thereon, he will operate a suitable lever and raise the plate or rails on such branch and apply the 35 brake to the moving car. It will be under-

stood that the braking power applied will be within certain limits dependent upon pressure exerted by the plate or rail 1 on the wheels 12.

I claim herein as my invention:

1. A car distributing yard having an elevated section of track, a plurality of branch tracks, switches for connecting the branches with the delivery side of the elevated section in combination with means arranged 50 along the branch tracks adapted, when shifted to operative position, to engage and shift a member of the brake mechanism in a car passing along a branch track.

2. A car distributing yard, having an elevated section of track, a plurality of branch tracks, switches for connecting the branches with the delivery side of the elevated section in combination with rails or plates arranged along the branch tracks, means for 55 shifting said plates or rails to and from operative positions, and a movable member on a car having an operative connection to the brake mechanism of the car and adapted to be shifted to apply the brakes by the 60 rails or plates when in operative positions.

3. A car distributing yard having an elevated section of track, a plurality of branch tracks and switches for connecting the branches with the delivery side of the elevated section in combination with means 70 operative from a common point for applying the brakes of cars passing along the several branches.

In testimony whereof, I have hereunto set 75 my hand.

GEORGE W. McMUNN.
